UNITED STATES PATENT OFFICE.

HIRAM BAKER, OF COLDWATER, MICHIGAN.

DEVICE FOR SHARPENING HORSESHOE-CALKS.

SPECIFICATION forming part of Letters Patent No. 250,482, dated December 6, 1881.

Application filed October 10, 1881. (Model.)

To all whom it may concern:

Be it known that I, HIRAM BAKER, a citizen of the United States of America, residing at Coldwater, in the county of Branch and State 5 of Michigan, have invented certain new and useful Improvements in Sharpening Horseshoe-Calks without Removing the Shoes; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this specification.

15 My invention relates to devices for sharpening horseshoe-calks; and it consists of the construction and arrangement of its several parts, as will be hereinafter fully set forth.

In the accompanying drawings, Figure 1 is 20 a plan view of my invention; Fig. 2, a vertical section, and Fig. 3 a view of the slide.

A is the iron frame in which is inclosed the operating mechanism. It is provided with a cross-bar, *a*, as shown.

25 Placed in elongated holes in the sides of the frame is the round file B. Upon one of its ends is secured the gear-wheel *b*, which engages with the gear-wheel *b'*, pivoted in the projection *a'*, and has secured to it a shaft running through 30 it to the crank *b²*, by which the file is rotated.

Placed within the frame is the spring-frame 35 C. Its ends are bent at right angles to its length, and have slots in their ends, which embrace and have bearing upon the journal-shaft of the file B. It has the rod *c* attached to it, which operates through a hole in the top of the frame.

Placed around the rod is the spiral spring *c'*, as shown.

40 Operating in grooves in the sides of the frame is the slide D. It is provided with recesses in its ends to prevent interference with the spring-

frame C, and is adjusted in any desired position by the thumb-screw *d*, which operates through the cross-bar *a*, and in a cup-shaped 45 disk, *d'*, in the slide D, as shown.

In the operation of my device the horse's hoof, with shoe attached, is held between the knees of the artisan, and the machine applied to the bottom of the shoe, the calks to be sharpened entering the recess between the file and bottom of the frame A. In sharpening the toe-calk the machine is placed on the hoof with the file end toward the toe of the shoe, and the calk is placed in the recess indicated. In sharpening the heel-calks the position of the machine is reversed, the file end being turned toward the heel and the heel-calks entered within the recess, as set forth. The file is then revolved, and the calks will be sharpened by contact with 55 it. During the operation the machine is held in position by the hand.

In the operation of the machine the bottom of the horseshoe rests upon the slide D, and the calk extends into the recess between the 60 file and frame A. It will be seen that by raising or lowering the slide the calk will be raised or lowered upon the file, as desired. In sharpening long calks the slide is raised a sufficient distance to bring the end of the calk against 65 the file, and when short calks are to be sharpened the slide is lowered to the proper distance above the file.

What I claim is—

In combination with the frame A and gear-wheel *b'*, the file B, provided with gear-wheel *b*, spring-frame C, spring *c'*, and adjustable slide D, all arranged and operating as set forth.

In testimony whereof I affix my signature in presence of two witnesses.

HIRAM BAKER.
